UNITED STATES PATENT OFFICE.

HENRY C. BAINBRIDGE, OF BROOKLYN, NEW YORK.

DESIGN FOR ENVELOPES.

Specification forming part of Design No. 11,138, dated April 8, 1879; application filed January 30, 1879.
[Term of patent 3½ years.]

To all whom it may concern:

Be it known that I, HENRY C. BAINBRIDGE, of the city of Brooklyn, in the county of Kings and State of New York, have originated and designed a Pattern for Envelopes, of which the following is a full, clear, and exact description, reference being had to the accompanying drawings, forming part of this specification.

A indicates the lower flap of the envelope, and B indicates the seal-flap thereof. The lower flap, A, is ornamented near its side edges by an embossed representation of ribbon, as indicated by a a. The seal-flap is also ornamented along its side and lower edges by an embossed representation of a ribbon, as indicated by b b c c, and the said flap is ornamented at its tip by an embossed representation of a bow, as indicated at d, the said bow presenting the appearance of a continuation of the ribbon represented and indicated by b b c c on the sides and lower edges of the said flap.

What I claim as my invention is—

The design for an envelope, comprising the lower flap, ornamented by the representation of a ribbon, a a, and the seal-flap, ornamented by the representation of a ribbon, b b c c, and bow d, the said bow presenting the appearance of a continuation of the ribbon indicated by b b c c, substantially as herein shown and described.
